United States Patent Office.

AURESTUS S. PERHAM, OF WASHINGTON, DISTRICT OF COLUMBIA, ASSIGNOR TO HIMSELF, ALONZO BELL, AND AMOS HADLEY, OF SAME PLACE.

Letters Patent No. 99,470, dated February 1, 1870.

IMPROVEMENT IN COMPOUND TOOL.

The Schedule referred to in these Letters Patent and making part of the same.

I, AURESTUS S. PERHAM, of Washington City, District of Columbia, have invented a new and useful Improvement in Combination Tools, of which the following is a specification.

The object of my invention is to combine several mechanical tools, such as are more commonly used by persons in every branch of business, in shop and in household, in one neat and compact body, and thus to provide both a means by which several tools may be kept together, and a convenient form for using them in this compact body; also, to combine several tools in such manner that they may be manufactured and supplied at an expense much less than when each tool is constructed complete in itself, and independent of others.

Thus, my invention consists in so constructing the handle of a hatchet, hammer, or other implement, that there may be encased in, and combined with it, several tools, such as screw-driver, chisel, can-opener, saw, and tape-measure, or other tools in lieu thereof, in such manner as to make it convenient to use them all from the handle in which they are encased and combined.

Figure 1, of the accompanying drawing, is a side view of the instrument embodying my invention.

Figure 2 represents one section of the handle of the instrument, the handle having been divided lengthwise through the centre, with the tools encased therein.

Figure 3 represents either end of the handle, or ferrule on the handle, with the orifice through which the tools are made to protrude, when desired for use; also, the "catch," which, by the aid of a spring connected with it, secures said tools firmly in place.

A is the handle of the hatchet, which should be made of hard wood, and may be constructed either of one solid piece of wood, or of two pieces of wood, of similar shape, united together flatwise, and secured by glue, rivet, or screw, and by the ferrules B B, on either end of the handle. The object of constructing the handle in two parts is to give it greater strength, and to better insert my improvements.

C is the hatchet, in the eye of which the handle is secured by the thumb-screw D, so that the handle may be taken out at pleasure by loosing the screw, thereby giving access to the tools confined in the end of the handle, which is inserted in the eye of the hatchet.

E is the claw of the hatchet, formed upon the back part of that portion of the hatchet opposite to the blade, which is used for hammering.

F F are the orifices, in either end of the handle or ferrule, through which the tools are made to protrude, when required for use.

G is a shallow groove, in the centre of the handle, about one-eighth by three-eighths of an inch, and running longitudinally through the handle.

H H are the tools, to be made of iron or steel, which fit closely in the groove G, in which they play.

The two tools, confined in either end of the handle, are united together at the ends, so that either tool, thus united, may be used by simply reversing them, so as to make the one required for immediate use to protrude from the orifice in the handle, while the other tool is upon the opposite end of the same piece of steel, and encased within the handle.

The tools H H are secured in position, when being used, by the catches or little slides I I, which play between the inner surface of the end of the ferrules B B, and the end of the wood of which the handle is constructed, and these catches are forced into the notches J J, in the edges of the tools H H, by the steel springs K K, which springs are secured by one end to the inner surface of the ferrules, and the other ends press against the ends of the "catches" or slides I I.

When the tools H H do not protrude from the orifices F F, these orifices are partially and sufficiently closed by the catches or slides I I, to prevent the tools in the handle from falling out voluntarily.

The "catches" are moved, and the orifices opened, by pressing upon the knobs L L, protruding from the under side of the ferrules.

M is a small brass ring, fastened to the end of a tape-measure, N, which is wound around a small metallic drum, O, encased in the handle, and which measure is divided off into feet, inches, and parts of inches, and the inches numbered.

Within the drum O, which revolves upon a small pivot in the centre, is a steel coil or spring, P, and when the tape-measure N is withdrawn from the orifice Q, by pulling upon the ring M, it winds up the spring P, which relaxes, and thereby draws the tape-measure back into its case by winding it upon the drum O.

Claim.

I claim, as my invention—

The implement herein described, composed of the handle A, hatchet C, claw E, screw-driver and chisel H, saw and can-opener H', and the tape-measure N, all being constructed and arranged to operate substantially in the manner and for the purpose specified.

AURESTUS S. PERHAM.
